(57) **CLAIM**

The ornamental design for a putter head with inserts, as shown and described.

DESCRIPTION

FIG. 1 is a front perspective view of the putter head with inserts.

FIG. 2 is a front view of the putter head with inserts.

FIG. 3 is a right-side view of the putter head with inserts.

FIG. 4 is a left-side view of the putter head with inserts.

FIG. 5 is a back view of the putter head with inserts.

FIG. 6 is a top view of the putter head with inserts.

FIG. 7 is a bottom view of the putter head with inserts; and, FIG. 8 is a rear perspective view of the putter head with inserts.

The broken line showing on the drawing views is included for the purpose of illustrating and forms no part of the claimed design.

1 Claim, 3 Drawing Sheets
